2,437,856

PRESSURE FLUID CONTROLLING DEVICE

Paul A. Lincoln, Bloomsbury, N. J., assignor to
Ingersoll-Rand Company, New York, N. Y., a
corporation of New Jersey

Application March 17, 1943, Serial No. 479,455

1 Claim. (Cl. 277—19)

1

This invention relates to fluid actuated machines, as for example a rock drill, and more particularly to a pressure fluid controlling device for controlling communication between pressure fluid supply and a plurality of different chambers of machines of this type.

One object of the invention is to facilitate the operation of the valve means serving to control communication between pressure fluid supply and such chambers.

A more specific object is to enable a pair of throttle valves to be manipulated by a single actuating member in such wise that pressure fluid may be valved selectively to one or to both of a pair of chambers.

Other objects will be in part obvious and in part pointed out hereinafter.

In the drawings accompanying this specification and in which similar reference numerals refer to similar parts,

Figure 1 is a side elevation of a rock drill of the stoper type equipped with a pressure fluid controlling device constructed in accordance with the practice of the invention.

Figure 2 is a vertical view, partly broken away, of the pressure fluid controlling device and portions of the rock drill utilizing such pressure fluid.

Figure 3 is a plan view, in section, taken through Figure 2 on the line 3—3 looking in the direction of the arrows, and

Figures 4 and 5 are transverse views taken, respectively, on the lines 4—4 and 5—5 through Figure 2.

Referring more particularly to the drawings, the invention is shown applied to a rock drill 20 of the stoper type having a pair of coaxially arranged cylinders 21 and 22 that are separated by the controlling device, designated in general by 23.

The cylinders 22 and 21 are clamped to the controlling device 23 by side rods 24, in a manner well known, and in the cylinder 21 is a percussive element or hammer 25 for actuating a working implement 26. The feeding cylinder 22 houses a piston 27 having a rod that projects from the free end of the cylinder and carries a pointer 28 for engagement with a surface 29 to support the rock drill.

The controlling device 23 comprises a casing 30 having a boss 31 at one end to extend into the cylinder 22 for centralizing these parts with respect to each other, and a plate 32 in the opposite end of the casing 30 extends into the cylinder 21 for holding said cylinder in coaxial relationship with the casing 30 and the cylinder 22. The casing 30 is recessed to form a supply chamber 33

2

for pressure fluid that may be introduced thereto through a supply port 34 in the casing 30.

A throttle valve 35 in the form of a cylindrical, flat plate is arranged at one end of the chamber 33 to control the flow of pressure fluid from the supply chamber to the hammer 25. The throttle valve 35 is rotatable to its different controlling positions and has a port or ports 36 to register with a supply passage 37 in the plate 32 for supplying pressure fluid first to suitable valve mechanism, only the chest 38 of which is shown, for distribution to the hammer 25. The throttle valve 35 seats on an end surface 39 of the plate 32 and is held against endwise movement in the direction of the chamber 33 by a ledge 40 on the wall of the chamber 33.

The supply of pressure fluid to the cylinder 22 is controlled by a separate throttle valve 41. This throttle valve is also rotatable and is arranged 20 in a bushing 42 in the side of the casing 30 to provide a bearing surface 43 for said throttle valve. The throttle valve 41 is of the plug type. It is arranged perpendicular to the axis of rotation of the throttle valve 35 and has an end 44 projecting exteriorly of the bushing to receive a lever 45 whereby the valve may be rotated. The lever 45 is held on the end 44 by a nut 46 and carries a detent 47 shown as a spring pressed ball for engagement with depressions 48 in the outer end 30 of the bushing 42 to lock the throttle valve 41 against unauthorized rotary movement.

The inner end of the valve 41 extends into the chamber 33 and has an axial passage 49 that opens into the chamber 33 and communicates at 35 its outer end with a radial port 50 leading to the periphery of the throttle valve. The port 50 is positioned to register, in what may be termed the open position of the throttle valve 41, with a supply passage 51 leading to the cylinder 22 through 40 the bushing 42 and the casing 30.

The throttle valve 41 also serves to control the exhaust of pressure fluid from the cylinder 22. It accordingly has a groove 52 extending along its surface to establish communication between 45 the supply passage 51 and with an atmospheric exhaust port 53 in the lever 45.

To the end that the throttle valves may be manipulated in a simplified manner and with a minimum of actuating elements said valves are 50 provided with means that cooperate with each other for transmitting rotary movement from one valve to the other, in the example shown, from the valve 41 to the valve 35. The throttle valve 35 is accordingly provided with gear teeth 54 on its 55 exposed end surface for engagement with gear

teeth 55 projecting from the periphery of an enlargement 56 on the inner end of the throttle valve 41.

In the drawings only three gear teeth are shown on each throttle valve but it is to be understood that the number may vary with the range of rotative movement of the valves required for establishing registry of their ports with the passages they control.

In order that the valve 41 may serve the additional function of a lock for the valve 35 when their teeth are out of engagement with each other and, at the same time, to permit rotary movement of the throttle valve 41 relatively to the valve 35, the latter valve is provided with an arcuate, radially extending groove 57 to receive the blank peripheral surface 58 of the enlargement 56. The radial edge 59 of the groove 57 adjacent the toothed portion of the throttle valve 35 preferably lies inside of the end surface of the said valve 35, and the blank portion of the enlargement 56 is notched as at 60 to prevent locking engagement of the edge 59 on the enlargement 56 during the rotation of the throttle valves.

The operation of the device is as follows: Whenever it is intended to operate the rock drill and with the throttle valves in the positions shown in Figure 5, the valve 41 is first rotated to a position to place the port 50 in registry with the supply passage 51. The pressure fluid thereby admitted into the feeding mechanism will extend it and press the pointer 28 firmly against the surface 29 and the working implement 26 against the work. This movement of the valve 41 may take place without disturbing the position of the throttle valve 35 since the gear teeth of the valves will then be out of engagement with each other and the valve 35 will be held in its closed position by the blank portion of the enlargement 56.

By rotating the valve 41 to the position required to establish registry of the port 50 with the supply passage 51 its toothed segment will be carried to a position to mesh with the teeth of the valve 35. Thus, when the valve 41 is rotated further in the direction described, its teeth will engage those of the valve 35 and cause the latter to be rotated to a position wherein the port 36 registers with the supply passage 37. Pressure fluid will then flow from the chamber 33 to the distributing valve mechanism of the rock drill for distribution to the cylinder 21.

From the foregoing description it will be seen that the entire drilling mechanism will first be extended to place it in the correct operative position and that the percussive element is next set in operation. Conversely, when it is intended to

discontinue drilling and to remove the drilling mechanism to another site, the throttle valve 41 is rotated in an opposite hand direction to that previously described. During its initial movement in this direction the valve 35 will also be rotated since its teeth are intermeshed with those of the valve 41 and will be carried to a position to cut-off the admission of pressure fluid to the percussive element while pressure fluid is still entrapped in the cylinder 22.

Upon further rotation of the valve 41 in the same direction its teeth will move out of mesh with the teeth of the valve 35. The latter will then be held against rotation by the enlargement 56 and the wall of the groove 57. When the valve 41 reaches the position in which the groove 52 registers with the supply passage 51 the pressure fluid in the cylinder 22 will escape to the atmosphere and the drilling mechanism may then be contracted for transportation to another drilling site.

I claim:

In a pressure fluid controlling device, the combination of a casing having a reservoir for pressure fluid and a pair of outlets and an inlet for the reservoir, a throttle valve of the rotary plate type to control communication between the reservoir and one of the outlets, teeth on a portion only of the periphery of the throttle valve, a rotary plug valve arranged perpendicularly to the axis of rotation of the throttle valve capable of movement independently of the throttle valve and having a passage to afford communication between the reservoir and the other outlet, and teeth on the end of the plug valve for selective engagement with the teeth on the throttle valve for transmitting rotary movement from the plug valve to the throttle valve.
